UNITED STATES PATENT OFFICE.

WILLIAM CHARLES CROCKER, OF SUTTON, ENGLAND.

FASTENER FOR LOOSE SHEETS OF PAPER OR OTHER MATERIAL.

Application filed April 20, 1926, Serial No. 163,187, and in Great Britain March 6, 1925.

This invention relates to devices for securing together loose sheets of paper or other like material, and has for its object to provide a fastener which is more easily and 5 cheaply manufactured than fasteners of a similar character which are at present in use.

The present invention consists of a fastener for loose sheets of paper or other material, comprising in combination a cord, a stop, 10 for example, a transverse tag secured to one end of said cord, an open framework, a loop extending inwardly from the periphery to substantially the centre of such framework adapted to adjustably and detachably 15 operate with the cord, and a cleat carried by said frame adapted to receive and fix the cord.

In order that this invention may be clearly understood and readily carried into practice, 20 reference may be had to the appended explanatory sheet of drawings, upon which:—

Figure 1 illustrates in elevation the two parts of a fastener constructed according to the present invention.

Figure 2 illustrates the present fastener in use.

One method of carrying the invention into effect comprises a cord *a* to which a tag *a*¹ is secured so as to lie in a transverse direction to the length of the cord. The cord is provided at its other end with a second tag *a*² which coincides with the length of the cord, and facilitates papers being threaded upon the cord.

Adapted to be attached to a point along the length of the cord *a* is a wire framework *b* of rectangular formation wherein one end *b*¹ of the wire is threaded through a loop *b*² in the other end of the wire which constitutes the frame, and is doubled back upon one side of the framework so as to lie upon the same and in adjacency thereto, (as shown particularly in Figure 2), such that, if the said end *b*¹ is lifted away from the side adjacent thereto, the end of the wire, due to its natural resiliency, springs back upon the said side and framework.

The free end *b*¹ of the wire so formed constitutes a cleat, and it may be provided at a point along its length with an indentation 50 *b*⁵ (Fig. 2) which extends above the side of the framework situated adjacent thereto.

That side *b*³ of the frame which lies opposite to the one over which the said cleat extends is preferably bent at its mid-point inwardly so as to form a loop *b*⁴ which extends from the periphery of the framework to substantially the centre of the same.

The operation of the device is as follows:—When the papers *c* have been threaded upon the cord *a* and are held against the transverse tag *a*¹ secured to one end thereof, the cord is slipped into the loop *b*⁴ until the cord is situated substantially at the centre of the said framework. The cord is 65 thereafter sprung under the cleat formed by free end *b*¹ of the wire, and is held, due to the natural resiliency of the same, fixed in that position.

What I claim as my invention and desire 70 to secure by Letters Patent is:—

1. A fastener for loose sheets of paper or other material, comprising in combination a cord, an abutment provided at one end of said cord, an open wire framework, an inwardly directed U-shaped part of said wire framework adapted to engage the cord, and a folded part of said wire framework adapted to serve as a cleat for the cord.

2. A fastener for loose sheets of paper or other material, comprising in combination a cord, an abutment provided at one end of said cord, an open frame bent from a single length of wire and having a loop at one extremity of the wire, a folded portion of the 85 wire engaging said loop and adapted to serve as a cleat, and an inwardly directed U-shaped formation on said wire adapted to adjustably and detachably cooperate with the cord.

In witness whereof I have hereunto set 90 my hand.

WILLIAM CHARLES CROCKER.
